WILLIAM A. TEBO, OF ANTHONY, RHODE ISLAND, ASSIGNOR TO DRAPER CORPORATION, OF HOPEDALE, MASSACHUSETTS, A CORPORATION OF MAINE.

AUTOMATICALLY THREADING LOOM SHUTTLE.

Application filed November 18, 1927. Serial No. 234,251.

This invention relates to automatically threading shuttles for looms and is more particularly directed to the thread tensioning means for regulating the tension applied to 5 the thread during weaving.

It is now the ordinary practice to provide filling replenishing shuttles of the automatically threading type with some kind of a tension device for controlling the delivery 10 of the thread from the shuttle during weaving. In some such cases, pieces of felt or fabric, or similar material are mounted adjacent the front end of the shuttle and act continuously upon the thread during weaving, 15 while in other cases the shuttle is provided with tensioning members which are yieldingly pressed towards each other to place tension upon the thread passing between them. In weaving with certain kinds 20 or characters of yarn or thread, such as, for instance, silk, artificial silk, rayon, or the like, it is desirable that the thread pass between tensioning members having opposed faces of considerable extent so that during 25 the weaving operation, and owing to the swirl of the thread as it is withdrawn from the shuttle, the thread may not be thrown entirely from between the tensioning members. On the other hand, when the thread is 30 continuously placed under tension by the faces of such tensioning members, it is liable to cut or wear into the surface thereof by the constant attrition of the thread during weaving.

One of the objects of the present invention is to provide tensioning members of the extensive face type for engagement with the thread, to relieve the action of the tensioning members upon the thread as the shuttle passes 35 through the shed and to automatically restore the action of the extensive faced tensioning members upon the thread as it enters the shuttle box, with the result that during the major portion of the operation of the 40 shuttle the face portions of the tensioning members are relieved from the scoring effect of the thread and yet when the shuttle enters the shuttle box sufficient tension is placed

upon the thread to insure a proper lay of the thread through the shed and from the cloth 50 selavage to the shuttle.

An important feature of the present invention therefore consists in an automatically threading loom shuttle having tensioning members which are under the influence 55 of yielding means normally tending to force them into engagement with the thread passing between them and a controller for the tensioning members which acts in opposition to the normally acting means to relieve the 60 tension on the thread as the shuttle passes through the shed and then frees the tensioning members to the action of the normally 65 acting means when the shuttle enters the shuttle box. The tensioning members are 70 preferably formed with extensive face thread-engaging portions, and such tensioning members are preferably mounted for movement towards and from each other in the longitudinally extending thread passage leading from the bobbin chamber to the side delivery eye.

The invention and novel features thereof will best be made clear from the following 75 description and the accompanying drawings of one good form of means for carrying out the purposes of the invention.

In the drawings:

Fig. 1 is a top plan view of an automatically threading loom shuttle provided with 80 the present invention;

Fig. 2 is an enlarged cross-section on the line 2-2 of Fig. 1;

Fig. 3 is a skeletonized view of the shuttle, showing more particularly in full lines the 85 means for controlling the tension upon the thread;

Fig. 4 is an exploded view of the tensioning members in their separated relation;

Fig. 5 is a horizontal sectional view of an 90 automatically threading shuttle provided with the present invention, showing the action of the controlling means when the shuttle enters the box and tension is applied to the thread; and

Fig. 6 is a modified form of the tensioning 95

members which may be advantageously employed in connection with the present invention.

The shuttle 1, which may be of the usual filling replenishing type, is provided with the bobbin chamber 2, the side delivery eye 3 and the longitudinally extending thread passage 4 between the bobbin chamber and side delivery eye, and, as shown in the present instance of the invention, the longitudinally extending thread passage 4 is preferably formed in the threading block 6 which may be of usual construction.

Mounted in the longitudinally extending thread passage 4 are the thread tensioning members which are normally under the influence of yielding means tending to move the tensioning members towards each other and into engagement with the thread during weaving. In the present instance of the invention, the tensioning members are shown as plates pivotally mounted in the longitudinal thread passage for movement towards and from each other under the influence of springs. As shown by Fig. 4, one of the tensioning members is formed by a base portion 7 having the lugs 8 provided with openings 9 which engage a fixed pin or axis 10 extending longitudinally of the thread passage. Extending upwardly from the base portion 7 of one of the tensioning members is a plate 11 having a broad face, as indicated in Fig. 4, for engagement with the thread, and at its upper portion the plate 11 is turned outwardly at 12 and is provided with a downwardly extending lip 13 which is adapted to engage a shoulder 14 formed in the threading block to limit the swinging movement of the tensioning member laterally of the thread passage under the action of the spring 15.

The tensioning member just described is provided with a finger 16 having an upper hook portion 17 and adapted to be engaged by the controlling means, as will presently appear.

The opposing tensioning member is formed with an appropriate base portion 18 having end lugs 19 and openings 20, whereby the tensioning member may be mounted upon the longitudinally extending pin 10 secured in the thread passage. Projecting upwardly from the base portion 18 of this tensioning member are the plates, which co-act with the plate 11 of the opposing tensioning member, to present a broad surface for engagement by the thread passing between the tensioning members. In the present instance of the invention, the upwardly extending plates 21 projecting from the base 18 are in separated relation and the upper portion of the tensioning plates 21 is provided with the downturned lips 22 which are adapted to engage a shoulder 23 formed at the side of the thread passage, to limit the movement of the tensioning member under the influence of its spring 24. The

springs 15 and 24 which act to relatively move the tensioning members normally towards each other, may be seated in suitable recesses formed in the side walls of the thread passage, and, if desired, the ends of the springs 15 and 24 may engage over pins 25 secured to the outer walls of the tensioning members to thereby maintain the springs in operative engagement with the respective tensioning members.

The two tensioning members may be variously contrived and one modified form thereof is indicated by Fig. 6 wherein the tensioning members 26 and 27 are formed as plates having the vertical corrugations 28 which act upon the thread passing between the tensioning members to bend or deflect the thread passing between them. The two tensioning members 26 and 27 in the modified form shown by Fig. 6 are provided with similar base portions to the tensioning member previously described, and one of the tensioning members is also provided with the upwardly extending finger 16.

From the construction thus far described it will be apparent that the two tensioning members in the present form of the invention are pivotally supported and extend upwardly in the longitudinally extending thread passage to present broad contacting thread-engaging faces to the thread passing between them, and the tensioning members, as previously described, are under the influence of yielding means, such as the springs 15 and 24, which normally act to relatively move the tensioning members in a direction to engage and clamp the thread passing between them. This general form of tensioning members has been found in practice to be especially well adapted for weaving with certain kinds and characters of yarn, because the broad thread-engaging faces of the tensioning members present surfaces sufficiently extensive to prevent the thread from being thrown from between the tensioning members during weaving.

As hereinbefore indicated, the present invention contemplates means for controlling the tensioning members so that during the flight of the shuttle through the shed little or no tension may be exerted upon the thread; whereas, when the shuttle enters the shuttle box the tensioning members will be freed to the normally acting springs 15 and 24 to force them into contact with the thread and apply the desired tension.

In the present instance of the invention, the controlling means is shown as an arm or lever 29 pivotally mounted at 30 in a recess 31 formed in the wall of the bobbin chamber, and the forwardly extending end portion 32 of the arm 29 engages the finger 16 of one of the tensioning members. The arm 29 is provided with a bent portion 33, in the present instance, which is normally under the

influence of a spring 34 mounted in a recess 35 formed in the wall of the bobbin chamber, and associated with the spring 34 is the adjusting plug 36 whereby the energy of the 5 spring 34 may be varied to suit the conditions of use. The energy of the spring 34 is greater than the energy of the spring acting on the tensioning member provided with the finger 16, with the result that under normal 10 conditions, with the shuttle not in the shuttle box, the tensioning members will be separated against the action of the normally acting springs 15 and 24.

The arm 29 is provided with an end portion 37 which extends through an opening 38 in the side wall of the shuttle and normally projects slightly beyond the side wall, as indicated in Fig. 1, so that when the shuttle enters the shuttle box, the end 37 of the arm 20 will engage the wall of the shuttle box and be turned upon its pivotal support 30 thereby moving the end 32 of the arm outwardly or away from the engaging finger 16, with the result that the normally acting 25 springs 15 and 24 will thereupon cause the tensioning members to move relatively towards each other and place tension upon the thread.

When the shuttle is picked and is passing 30 through the shed it is desirable that there be no substantial tension upon the thread as it is delivered from the shuttle, and this is effected in the present instance of the invention by the movement of the arm 29 upon its 35 pivotal support under the action of the spring 34 which, when the shuttle is out of the shuttle box, acts upon the finger 16 of the tensioning member and relieves the tension on the thread in opposition to the normally acting springs 15 and 24. When, however, 40 the shuttle enters the shuttle box, the end 37 of the arm 29 will be moved inwardly by engagement with the wall of the shuttle box, as indicated in Fig. 5, whereupon the tensioning members will be freed to the 45 operation of their normally acting means, such as the springs 15 and 24, to move towards each other, engage the thread, and place the desired tension thereon as the shuttle enters the box and comes to rest at the end of its 50 flight.

From the construction described as one form of the present invention wherein tensioning members of the broad-faced type are employed for tensioning the thread, it will 55 be apparent that during the passage of the shuttle through the shed the thread will be relieved of the tensioning effect of the tensioning members by the controlling means 60 which acts under the influence of the spring 34 to effectively separate and release the tensioning members from engagement or substantial engagement with the thread, but when the shuttle enters the shuttle box and 65 tension is desired to tension the thread prop-

erly in the shed and for the action of the weft fork and parting mechanism, if any, the thread will be straightened out and all kinks and other objectionable deflections of the thread will be overcome, because at this time 70 the controller frees the tensioning members to the operation of the normally acting means which tends to move them into thread engagement. Of course, various modifications and changes may be made in the details of the 75 present invention without departing from the true scope thereof, and the tensioning members themselves may be variously formed to present broad thread-engaging faces to the thread for tensioning means, but I believe 80 this is the first instance in the art wherein separate tensioning members normally under the influence of means for moving them into thread engagement are controlled as hereinbefore described by controlling means which 85 acts in opposition to the normally acting means to relieve the tension on the thread as the shuttle passes through the shed, and then frees the tensioning members to the action of the normally acting means. 90

Where the controller is constituted as an arm 29, as indicated, it is preferable to provide the wall of the bobbin chamber with a recess 39 in which the arm 29 may be housed so that it does not interfere with replenishment of filling. 95

What is claimed is:

1. In an automatically threading loom shuttle having a bobbin chamber, a side delivery eye, and a longitudinally extending threading passage, tensioning members mounted in the threading passage, spring means normally acting upon the tensioning members to hold them in thread tensioning position, and a controller acting on the tensioning members 100 in opposition to the spring means to relieve the tension on the thread during the passage of the shuttle through the shed and adapted to free the tensioning members to the normally acting spring means to enable said spring 105 means to place tension on the thread as the shuttle enters the shuttle box. 110

2. In an automatically threading loom shuttle having a bobbin chamber, a side delivery eye, and a longitudinally extending 115 threading passage, tensioning members mounted in the threading passage, spring means normally acting to move the tensioning members relatively in a direction of approach to place tension on the thread passing between said members, means for limiting the relative movement of said members in said direction, and a controller acting on the tensioning members in opposition to said spring means to relieve the tension on the 120 thread during the passage of the shuttle through the shed and means for moving the actuator to free the tensioning members to the normally acting spring means to enable 125 said spring means to place tension on the 130

thread as the shuttle enters the shuttle box.

3. In an automatically threading loom shuttle having a bobbin chamber, a side delivery eye, and a longitudinally extending 70
5 threading passage, two tensioning members mounted in the threading passage, spring means normally acting to move the tensioning members relatively in a direction of approach to place tension on the thread passing 10 between said members, and a controller acting on the tensioning members in opposition to said spring means to relieve the tension on the thread during the passage of the shuttle through the shed and adapted to free the tensioning members to the normally acting 15
15 spring means as the shuttle enters the shuttle box.

4. In an automatically threading loom shuttle having a bobbin chamber, a side delivery eye, and a longitudinally extending 75
20 thread passage, tensioning members mounted in the thread passage, spring means normally acting to move one of the tensioning members relative to the other to place tension on 25
25 the thread passing between said members in the longitudinal thread passage, and controlling means for the tensioning members acting in opposition to said spring means to relieve the tension on the thread during the 30
30 passage of the shuttle through the shed and to free the tensioning members to the action of the normally acting spring means as the shuttle enters the shuttle box.

5. In an automatically threading loom 90
35 shuttle having a bobbin chamber, a side delivery eye, and a longitudinally extending thread passage, tensioning members having thread deflecting surfaces and mounted for relative movement in the thread passage, 95
40 yielding means normally acting to relatively move the tensioning members in a direction to cause the thread deflecting surfaces to engage the thread passing between them, and a controller operatively connected with at 95
45 least one of said tensioning members to move them relatively in a direction of separation to render said yielding means ineffectual to tension on the thread as the shuttle passes through the shed and restore them to the 100
50 normally acting yielding means that the latter may act to move the tensioning members in thread tensioning position as the shuttle enters the shuttle box.

6. An automatically threading loom shuttle having a bobbin chamber, a side delivery 105
55 eye, and a longitudinally extending thread passage, tensioning members between which the thread passes, spring means normally acting to cause said tensioning members to place 110
60 tension on the thread passing between them, a controller for the tensioning members, a spring acting on the controller in opposition to said normally acting spring means to relieve tension on the thread as the shuttle 115
65 passes through the shed, and means acting on 120
125

the controller as the shuttle enters the shuttle box to restore the tensioning members to the action of the normally acting spring means that the tensioning members may tension the thread.

7. An automatically threading loom shuttle 70
having a bobbin chamber, a side delivery eye, and a longitudinally extending thread passage, tensioning members mounted for relative swinging movement in the longitudinally extending thread passage and between which the thread passes, means normally acting to cause said tensioning members to place tension on the thread passing between them, and a controller for the tensioning 75
80 members, a controller spring of greater power than the means normally acting on the tensioning members and operating in opposition to the normally acting means during the passage of the shuttle through the shed to relieve the tension on the thread and means acting on the controller to free the tensioning members to the normally acting 85
means as the shuttle enters the shuttle box.

8. An automatically threading loom shuttle 90
having a bobbin chamber, a side delivery eye, and a longitudinally extending thread passage, a pair of pivotally mounted tensioning members in the longitudinal thread passage 95
95 between which the thread passes, springs normally acting to move the tensioning members relatively to engage and tension the thread, and a controller acting on one of said tensioning members in opposition to the said springs to separate said tensioning members 100
and relieve the tension on the thread as the shuttle passes through the shed and constructed and arranged to release the said springs to place tension on the thread as the shuttle enters the shuttle box.

9. In an automatically threading loom shuttle having a bobbin chamber and side delivery eye, a threading block between the bobbin chamber and side delivery eye having a longitudinally extending thread passage, broad faced tensioning members supported by the threading block in the longitudinal thread passage, normally acting yielding means for relatively moving one of the tensioning members to place tension upon the thread passing between them, and a controller acting on one of the tensioning members in opposition to the said normally acting yielding means to relieve tension on the thread during the passage of the shuttle through the shed and constructed and arranged to free the tensioning member to the normally acting yielding means as the shuttle enters the shuttle box that said normally acting means may then be effective to place tension on the thread.

10. In an automatically threading loom shuttle having a bobbin chamber, a side delivery eye, and a longitudinally extending thread passage, tensioning members mounted 130
130

in the threading passage and provided with spring means for normally urging them to the thread tensioning position, a controller constructed to relieve the action of the tension members on the thread, and means for rendering said controller active during the passage of the shuttle and for rendering it inactive during the boxing of the shuttle where-
5 by the thread is tensioned by said spring urged members as the shuttle enters the shuttle box and is relieved from tension thereby during its passage through the shed.

In testimony whereof, I have signed my name to this specification.

WILLIAM A. TEBO.
